UNITED STATES PATENT OFFICE.

GEORGE RITTER, OF WOODBRIDGE, NEW JERSEY, ASSIGNOR TO THE BARBER ASPHALT COMPANY, OF PHILADELPHIA, PENNSYLVANIA, A CORPORATION OF WEST VIRGINIA.

STRIP SHINGLE.

Application filed December 21, 1925. Serial No. 78,624.

This invention relates to weather-proof surface coverings and more particularly to that species known in the art as strip shingles, in contradistinction to the conventional units. Shingles of the type referred to are customarily fabricated of flexible material impregnated with bituminous substance and coated with a mineral surfacing suitably embedded or rolled therein to impart the required weather resistant qualities.

An object of this invention is to economically produce strip shingles having a novel and unique exposure outline, which strips, when laid in staggered overlapping relation, present the appearance of individually laid hexagonal shingles.

Another object of the present improvements is to provide strip shingles, which simulate hexagonally pointed shingles spaced at disconnected intervals laterally or longitudinally of the surface covered.

A further object is to furnish a novel type of strip shingle which interlocks with those of adjacent rows and produces a substantially two-ply surface covering.

With the foregoing and other objects in view this invention consists essentially in the form of shingle strip hereinafter described, typically illustrated by the accompanying sheet of drawings, and tersely defined with respect to novel features—as well as scope—in the subjoined claims.

In the drawings:

Fig. I, is a view in plan illustrative of the manner in which my novel shingle strips are severed from standard width material without waste.

Fig. II, is a plan view of a surface covered with shingle strips in accordance with this invention.

Fig. III, is a fragmentary plan section illustrating the interlocking phase of my novel shingle strips; and,

Fig. IV, is a sectional view taken as indicated by the arrowed lines IV—IV in Fig. III.

In carrying out the invention I preferably make use of standard width flexible, non-porous and weather-proof, material having a transverse dimension suitable to produce, when longitudinally and laterally severed, the shingle strips in staggered relation without waste. Such a length of material is comprehensively designated 5 by dot-and-

dash lines in Fig. I, and it is longitudinally 55 severed at 6 by any appropriate means, and transversely cut at 7 to afford successive individual strip shingles 8 in alternating right-and-left-hand relation.

The individual strip shingles 8 being counterparts of one another I will specifically outline the form of one only to avoid repetitive description. Accordingly, it is to be observed that the strip shingle 8 is configured to afford, as best evidenced by the 60 shaded portion of Fig. I, an upper straight edge 9 with rectangularly disposed ends 10; whereas the lower edge is of undulate character providing relatively disconnected quasihexagonal points 11, each terminating 65 with a retrovertible tip 12. More specifically set forth, the points 11 are separated from the body portion of the strip shingle 8 by end recessions 13 and an intermediate notch 14 having edges 15 parallel with the 70 upper straight edge 9; whereas each point 11, is bounded by two reversely directed oblique edges 16, opposed inwardly converging shorter edges 17, and a creasing 18 that separates the retrovertible tip 12 therefrom. 75 The tip 12, it is to be noted, also is bounded by a lower edge 19 parallel with the strip upper edge 9, and inwardly converging side edges 20. Furthermore, the tip 12 is the 80 counterpart in configuration of the notch 14, 85 while the recessions 13 are complemental and each the half of said notch; or, in other words, any two adjoining recessions 13 equal an individual notch 14, as will be well understood on an examination of the drawings. 90

Strip shingles 8 of the character described are laid as follows:

A starting strip 21 is first attached to the roof or other surface in any of the well known ways, whereupon the first or lower 95 row of strip shingles 8 are secured in end to end abutting relation with the retroverted tips 12 engaged thereunder, as will be easily appreciated from an examination of Fig. II, more particularly. Successive rows of 100 overlapping strip shingles 8 are similarly laid with the retroverted tips 12, passed by way of the notches 14 and adjoining recessions 13, below the body portions of the units in the immediately preceding row, 105 whereupon they are secured in place by nails 22 in accordance with conventional practice. At this point it is well to note that

the retrovertible tips 12 are cut to taper slightly outwards, and the advantage thereof will be well appreciated from Fig. III, wherein it is noticeable that the notch 14 is wider along the edge 15 than the tip 12 is at the fold or creasing 18. This dimensional difference provides side clearances that permit for lateral adjustment of the strip shingles 8, and at the same time provision is afforded for the easier insertion of the tip 12 under the subjacent strip 8, due to the trapeziform contour accorded the retrovertible tips 12 and notches 14. This feature of the invention is deemed highly important, as it overcomes the objections incident to parallel sided tips, which do not readily flex to inequalities of the surface being covered. Furthermore, when laying shingles having parallel sided tips sub-surface inequalities tend to spread the shingle units and thereby render the insertion of a parallel sided tip very difficult, and in many instances practically impossible. My trapeziform tip 12 and complementarily configured notch 14, eliminates all the aforesaid objections; whereas it is far more readily retroverted along the creasing 18 as the angular corners 23 thereof provide guidance whereby any inaccuracy in folding would be readily detected.

From the foregoing, as well as on reference to Fig. II of the drawings, it will be obvious that my novel strip shingles 8, when laid, provide a surface covering which has the distinctive appearance of shingles having hexagonal points but spaced at intervals laterally of the surface covered; whereas

the interlocked connection of the successively laid units is so apparent as not to need further explanation herein, while the substantially two-ply covering phase of this invention is clearly understandable from Figs. II and IV, more particularly.

Having thus described my invention, I claim:

1. A weatherproof surface covering composed of aligned strip shingles laid in overlapping relatively staggered rows; each strip shingle embodying quasi-hexagonal points, an intervening complemental cut out portion, and flanking recessions of similar semi-contour; and retrovertible portions integral with said points having inwardly converging side edges whereby successively laid strip shingles interlock those of an adjacent row with side clearances whereby lateral adjustment may be effected.

2. A weatherproof surface covering composed of aligned strip shingles laid in overlapping relatively staggered rows; each strip shingle embodying quasi-hexagonal points, an intervening complemental cut out portion and flanking recessions of similar semi-contour; and trapeziform retrovertible tips co-extensive with each point and having inwardly converging side edges, said tips when retroverted being adapted to interlock the cut out and adjoining flanking recessions of subjacent strips with clearance for lateral movement.

In testimony whereof, I have hereunto signed my name at Maurer, N. J., this 12th day of December, 1925.

GEORGE RITTER.
